UNITED STATES PATENT OFFICE.

WILHELM E. BAHR, OF OSCEOLA, NEBRASKA.

TRAP GUN.

Application filed September 6, 1922. Serial No. 586,416.

To all whom it may concern:

Be it known that I, WILHELM E. BAHR, a citizen of the United States, residing at Osceola, in the county of Polk and State of Nebraska, have invented new and useful Improvements in Trap Guns, of which the following is a specification.

The object of my said invention is the provision of a simple and desirable trap gun 10 designed more particularly for the killing of small fur bearing animals.

To the attainment of the foregoing, the invention consists in the improvement as hereinafter described and definitely claimed.

15 In the accompanying drawings, forming part of this specification:—

Figure 1 is a side elevation of the trap gun constituting the preferred embodiment of my invention with the parts in the positions they occupy precedent to cocking of the gun or after firing thereof.

Figure 2 is a similar view showing the gun set or cocked.

Figure 3 is an enlarged detail section 25 showing the firing pin of the gun and the parts adjacent thereto and also showing a cartridge in the barrel.

Figure 4 is an enlarged detail section 30 showing the arrangement of the frame and stake.

Figure 5 is an enlarged detail section showing the adjustable connection of the guide eye to the hanger on the barrel.

Similar numerals of reference designate 35 corresponding parts in all of the views of the drawings.

Among other elements my novel trap gun comprises a barrel 1, enlarged and threaded at its rear end as designated by 2. Ad- 40 justably fixed by a set screw 3 or other appropriate means on the barrel 1 is a hanger 4 in the form of a metallic strap and pro- 45 vided with apertures 5. The said apertures 5 are provided for the adjustable position- 50 ing of a guide eye 6 on which is a shank 7, Figure 5, for use in conjunction with a wing nut 8.

In combination with the said barrel 1 I 55 employ a breech member 9 on which is a forwardly extending tubular projection 10, the rear portion of the interior of which is reduced and threaded as designated by 11. This provision is made in order that the barrel may be expeditiously and easily dis- 60 associated from the breech for the placing of a cartridge 12 in the barrel, after which

the barrel may be turned into the tubular projection of the breech to the position shown in Figure 3, where both barrel and cartridge are in readiness for firing. A cas- 60 ing plug 13 is threaded into the breech 9 from the rear end of said breech, and in the casing plug is a firing pin 14 yieldingly maintained in the position shown in Figure 3 by a spring 15, the said spring 15 being 65 interposed between a sub-plug 16 in the inner end of the casing plug 13 and an enlarge- 70 ment 17 on the firing pin.

The breech 9 is carried by a body 18 and is preferably formed integral with the body 70 18, and as designated by 19 in Figures 1, 2 and 4 the body 18 is disposed in and piv- 75 otally connected to a bifurcated yoke 20. This yoke 20 is swivelled on a stake 21 which is designed to be driven into the ground or 75 into any available object with a view to maintaining the trap gun in working po- 80 sition.

Pivoted at 22 on the body 18 is a lever hammer 23, the upper portion of which is 80 opposed to the firing pin 14, and the lower portion of which is connected to one end of a retractile spring 24. The opposite end of the spring 24 is connected to an eye 25 on the pintle 26 of a sear lever 27. The lever 85 27 and the pintle 26 are carried by an ex- 90 tension plate 28, fixedly attached at 29 to the body 18. It will also be noticed that a retractile spring 30 is interposed between and connected to the lower arm of the sear 95 lever 27 and the plate 28.

Pivots connected to and extending for- 90 wardly from the lower arm of the sear lever 27 is a bait rod 31, said rod being disposed and guided in the eye 6 and being provided 95 at its forward end with a hook 32 designed to hold bait in proper position relative to the muzzle of the barrel 1.

It will be apparent from the foregoing 100 that when an animal pulls on bait attached to the rod 31 in the manner described, the sear lever 27 will be rocked against the ac- 105 tion of the spring 30 and in consequence the said sear lever will release the hammer 23, whereupon the spring 24 will powerfully 110 impel the hammer against the firing pin 14 and thereby explode the cartridge 12 and kill the animal. To set or cock the gun it is simply necessary to move the hammer 23 from the position shown in Figure 1 to the position shown in Figure 2, the beveled por- 115 tion 40 of the hammer being adapted to

ride past the toe 41 of the sear lever 27 so as to enable the said sear lever to snap into engagement with the recess 42 in the hammer 23.

5 In virtue of the gun being pivotally mounted or swiveled on the stake 21 as designed it will be manifest that the gun cannot be fired until an animal exerts a straight pull on the rod 31. It will also be 10 manifest that the firing pin is susceptible of being readily removed and replaced.

The adjustability of the guide eye 6 in the hanger or regulating slide 4 of the gun is also advantageous, and it will be noted 15 that the barrel 1 is adapted to be adjusted in and adjustably fixed to the hanger or regulating slide 4.

The adaptability of the rod 31 to be regulated—i. e., raised or lowered is important inasmuch as the gun can thereby be regulated for large or small animals. Moreover the gun can be carried in a loaded state without danger, the parts being 20 preferably positioned in that case as shown 25 in Figure 1.

As best shown in Figure 4 the body 18 is preferably provided in front of its center of movement with a foot 50 which by bearing on the yoke 20 serves to support the body 18 30 in proper working position.

I would also have it understood that in practice the gun is made sufficiently heavy to prevent jumping of the gun when the same is discharged.

35 I have entered into a detailed description of the construction and relative arrangement

of the parts embraced in the present and preferred embodiment of my invention in order to impart a full, clear and exact understanding of the said embodiment. I do not desire, however, to be understood as confining myself to the specific construction and relative arrangement of parts inasmuch as in the future practice of the invention various changes and modifications may be made such as fall within the scope of my invention as defined in my appended claim.

Having described my invention, what I claim and desire to secure by Letters Patent, 50 is:—

In a trap gun, a breech portion having a plug socket and a pin aperture disposed concentrically of the socket, a plug detachably secured in the socket and having its inner end bearing against the inner wall of the socket, the plug having a shoulder which bears against the face of the breech portion, a firing pin passing through the plug and the pin aperture, the said plug having a chamber which receives the intermediate 55 portion of the firing pin, the firing pin having an abutment which is slidably received in the chamber, a sub-plug closing the end of the chamber and through which the firing pin passes, said sub-plug adapted to bear 60 against the inner wall of the socket and a spring housed within the chamber and bearing at one end against the shoulder and at its opposite end against the sub-plug.

65 In testimony whereof, I affix my signature.

70 WILHELM E. BAHR.
